Attorney.

UNITED STATES PATENT OFFICE

2,470,397

SWIVEL CHAIR BASE

Evan S. Harter, Sturgis, Mich., assignor to Harter Corporation, Sturgis, Mich., a corporation of Michigan.

Application March 19, 1948, Serial No. 15,771.

12 Claims. (Cl. 248—194)

1

This invention relates to improvements in base or pedestal for swivel chairs.

The main objects of this invention are:

First, to provide a base or pedestal for swivel chairs which may be very economically produced, is light in weight and at the same time strong and rigid.

Second, to provide a base or pedestal for swivel chairs which is formed of relatively few parts, and one in which the parts are assembled in a 10 mutually bracing and supporting relation.

Further objects, and objects relating to details and economies of the invention will definitely appear from the description to follow. The invention is pointed out in the claims. A preferred embodiment of the apparatus for carrying out the method of the invention is clearly illustrated in the accompanying drawing in which:

Fig. 1 is a fragmentary elevational view partially in vertical section on a line corresponding to 1—1 of Fig. 2, portions of a chair seat and its spindle being indicated by dotted lines to show the relationship of the parts.

Fig. 2 is an inverted view of the base or pedestal with the caster wheels and their sockets removed.

Fig. 3 is an enlarged fragmentary view in section on a line corresponding to line 3—3 of Fig. 2.

Fig. 4 is a perspective view of one of the U-shaped leg members.

Fig. 5 is an elevational view of the cruciformed center member.

Fig. 6 is an enlarged sectional view on a line 6—6 of Fig. 2.

The embodiment of my invention, illustrated comprises the generally cruciform center member 1, formed as a stamping, the arm portions terminating in tubular end portions 2. The center member is of generally concavo-convex shape. The side walls or flanges 3 between the arm portions are inwardly curved and merge into the arm portions. The leg members 4 are formed of tubular stock and are of U-shape, each member constituting a pair of legs 5 having downturned outer ends 6.

The center member 1 is initially formed with the sides 7 of its arms projecting downwardly in parallel relation as is shown in Fig. 5. The pair of leg members are arranged in oppositely disposed relation, as shown in Fig. 2, with the legs between these flange-like parts 7. The flange-like parts 7 are then bent around the legs 4 to closely embrace the same and the edges of the parts 7 welded together and to the undersides of the legs as is indicated at 8 in Figs. 2 and 6 in the drawings. These welds are preferably arc welds.

The tubular spindle socket 9 is arranged through an opening 10 in the center member and between the bights of the leg members and se-

2

cured thereto by the welds 11. The spindle socket is also welded to the top of the center member as indicated at 12. This results in a very secure coacting bracing relationship for the spindle socket, the center member, and the leg members. The upper end of the socket member is flanged outwardly at 13 to provide a bearing for the nut member of the seat spindle indicated by dotted lines in the Fig. 1. Caster wheel sockets 14 at their lower ends are inserted in the downwardly directed ends of the legs. These provide a finish for the outer ends of the legs as well as reinforces therefor and supports the spindles of the caster wheels 15.

With the parts thus arranged, I provide a structure which may be very economically produced, is strong and rigid even when formed of comparatively light material and is attractive in appearance.

I have not attempted to illustrate various adaptations which I contemplate as it is believed that this disclosure will enable those skilled in the art to embody or adapt my invention as may be desired.

Having thus described my invention, what I claim as new and desire to secure by Letters Patent is:

1. A chair base or pedestal comprising a cruciform center member of generally concavo-convex shape facing downwardly and having inwardly curved side walls between the arms thereof, a pair of oppositely disposed tubular U-shaped leg members each constituting a pair of legs, the outer ends of the legs being turned downwardly, said leg members being disposed with their bights within the side walls of the center member and with their legs within the arms thereof, the arms of the center member being clamped around the legs with the edges of the arms on the undersides thereof and welded together and to the undersides of the legs, a tubular spindle socket member disposed centrally through the top of the center member and between the bights of the leg members in supported engagement therewith and welded thereto, the socket member being also welded to the top of the center member, the upper end of the socket member being flanged outwardly to provide a spindle bearing element, and caster wheel sockets having bead-like flanges at their lower ends inserted in the downturned ends of said leg member with their said bead-like flanges abutting the ends of the legs.

2. A chair base or pedestal comprising a cruciform center member of generally concavo-convex shape facing downwardly and having inwardly curved side walls between the arms thereof, a pair of oppositely disposed tubular U-shaped leg members each constituting a pair of legs, said leg members being disposed with their bights within the side walls of the center member and with

their legs within the arms thereof, the arms of the center member being clamped around the legs with the edges of the arms on the under sides thereof and welded together and to the under sides of the legs, a tubular spindle socket member disposed centrally through the top of the center member and between the bights of the leg members in supported engagement therewith and welded thereto, the socket member being also welded to the top of the center member.

3. A chair base or pedestal comprising a cruciform center member of generally concavo-convex shape facing downwardly and having inwardly curved side walls between the arms thereof, a pair of oppositely disposed tubular U-shaped leg members each constituting a pair of legs, the outer ends of the legs being turned downwardly, said leg members being disposed with their bights within the center member and with their legs within the arms thereof which embrace and are welded to the legs, a spindle socket member disposed centrally through the top of the center member and between the bights of the leg members and welded thereto, the socket member being also welded to the top of the center member, and caster wheel sockets having flanges at their lower ends inserted in the downturned ends of said leg member with their said flanges abutting the ends of the legs.

4. A chair base or pedestal comprising a cruciform center member of generally concavo-convex shape facing downwardly and having inwardly curved side walls between the arms thereof, a pair of oppositely disposed tubular U-shaped leg members each constituting a pair of legs, said leg members being disposed with their bights within the center member and with their legs within the arms thereof which embrace and are welded to the legs, a spindle socket member disposed centrally through the top of the center member and between the bights of the leg members and welded thereto, the socket member being also welded to the top of the center member.

5. A chair base or pedestal comprising a cruciform center member of bendable sheet stock, a pair of oppositely disposed U-shaped leg members each constituting a pair of legs, the bights of the leg members being disposed within said center member, the arms of the center member being disposed to embrace the legs and being welded thereto, and a spindle socket disposed centrally through the top of the center member and between the bights of the leg member and welded thereto and to the top of the center member whereby the leg members constitute bracing and supporting elements for the spindle socket.

6. A chair base or pedestal comprising a cruciform center member having tubular arm portions and inwardly curved flanges between the arm portions merging into said tubular arm portions, U-shaped leg members each constituting a pair of legs disposed with their legs within said arm portions of said center member and fixedly secured therein, and their bight portions within the flanges of said center member, and a spindle socket disposed through the top of the center member and between the bights of the leg members and fixedly secured thereto and to the top member, the leg members constituting supporting and bracing elements for the socket member.

7. A chair base or pedestal comprising a cruciform center member having tubular arm portions

and inwardly curved flanges between the arm portions merging into said tubular arm portions, U-shaped leg members each constituting a pair of legs disposed with their legs within said arm portions of said center member and fixedly secured therein, and their bight portions within the flanges of said center member.

8. A chair base or pedestal comprising a cruciform center member of generally concavo-convex shape facing downwardly and having inwardly curved side walls between the arms thereof, a pair of oppositely disposed U-shaped leg members each constituting a pair of legs, the bights of the leg members being disposed within said center member with the legs within the arms of the center member and secured thereto, and a spindle socket disposed centrally through the top of the center member and between the bights of the leg member and secured thereto whereby the leg members constitute bracing and supporting elements for the spindle socket.

9. A chair base or pedestal comprising a cruciform center member of generally concavo-convex shape facing downwardly and having inwardly curved side walls between the arms thereof, a pair of oppositely disposed U-shaped leg members each constituting a pair of legs, the bights of the leg members being disposed within said center member with the legs within the arms of the center member and secured thereto.

10. A chair base or pedestal comprising a cruciform center member, U-shaped leg members each constituting a pair of legs disposed and their legs within the arms of said center member and fixedly secured therein, their bight portions within said center member, and a spindle socket disposed through the top of the center member and between the bights of the leg members and fixedly secured thereto and to the top member, the leg members constituting supporting and bracing elements for the socket member.

11. A chair base or pedestal comprising a cruciform center member having downturned side flanges between the arms thereof, a pair of oppositely disposed U-shaped leg members each constituting a pair of legs, said leg members being disposed with their bights within the center member and with their legs within the arms thereof with the arms of the center member embracing and fixedly secured to the legs, and a spindle socket member disposed centrally through the top of the center member and between the bights of the leg members and secured thereto, the socket member being also secured to the top of the center member.

12. A chair base or pedestal comprising a cruciform center member having downturned side flanges between the arms thereof, a pair of oppositely disposed U-shaped leg members each constituting a pair of legs, said leg members being disposed with their bights within the center member and with their legs within the arms thereof with the arms of the center member embracing and fixedly secured to the legs.
